CELL TYPE WOOD BOXES

Floyd D. Flexon, Godfrey, Ill., assignor to Owens-Illinois
Glass Company, a corporation of Ohio

Application March 21, 1956, Serial No. 572,977

1 Claim. (Cl. 217—22)

The present invention relates to improvements in cell type wood boxes such, for example, as those widely used in the soft drink trade for delivering such merchandise in bottles to the retailer.

It has been standard practice in the trade to form and secure the cell or partition strips in wood boxes of the type herein involved, that if replacement of any or all of the strips should become necessary, considerable labor is required and it is also probable that the box proper and perhaps theretofore undamaged partition strips will be so mutilated in the process as to render the structure unfit for future use. Such arises in some instances from the fact that screws or nails are employed to secure the side and end walls to the adjacent ends of the partition strips. Alternatively metal strips or often bands are secured over the top edges of the box end walls to hold the ends of the partition strips in grooves that have been provided in the inner face of such end walls. These metal strips are very securely nailed in place. Obviously, removal of such partition strips, irrespective of which method of attachment is employed, cannot be effected easily and, as stated above, may and very frequently does result in the explained serious mutilation of the box and quite often breaking some of the partition strips.

An object of my invention is the provision of simple and effective means whereby a full high partition assembly unit may be fitted into full height grooves in the end and side walls of wood cases in such fashion as to facilitate not only initial placement, but removal and replacement of such assembly units, all without any damage whatsoever to the wood case or partition strips.

Another object is the provision of a partition assembly in which the several strips are so interlocked that the entire unit will be removably yet securely mounted within the wood box incident to direct attachment or fastening of only one transverse partition strip to the box.

A further object of my invention is the provision of a readily removable partition assembly facilitating conversion of a standard size wood box or case for use in carrying, for example, either twenty-four soda bottles or, if desired, four conventional paper-board bottle carriers, each of which contains six bottles.

Other objects will be in part apparent and in part pointed out hereinafter.

In the drawings:

Fig. 1 is a perspective view of a twenty-four cell wood box incorporating my invention.

Fig. 2 is a fragmentary detail perspective view of the partition assembly unit positioned immediately above a portion of a wood box.

Fig. 3 is a fragmentary detail perspective view showing the manner in which the locking center cross strip and one of the longitudinal partition strips are interlocked.

Fig. 4 is a perspective view illustrating the manner in which the structure shown in Fig. 1 can be converted for the purpose of accommodating four conventional

2

paper-board bottle carriers, each of which will contain six bottles.

In that embodiment of my invention illustrated in Figs. 1, 2 and 3, the wood box or case 10 comprises a rectangular bottom 11 and upstanding interconnected end and side walls 12 and 13 respectively. Since this particular box is intended to accommodate twenty-four bottles and to that end includes twenty-four cells or pockets, the following structure is utilized. On the inner face of each side wall 13, five equally spaced parallel vertical grooves 14 are formed, each extending the full height of and opening through the upper and lower margins of such walls. In each end wall 12, on the inner side surface thereof, are three vertical grooves 15, such being spaced apart equally longitudinally of the wall and so related to the side walls 13 and grooves 14 therein that a partition assembly unit utilizing all of the grooves will provide the twenty-four cells mentioned above. Each end wall 12 may advantageously be provided with a hand opening 16 to facilitate carrying the box or case.

In the illustrated embodiment of the partition or cell assembly unit 17 for the twenty-four cell box, it comprises three longitudinal partition strips 18, the opposite ends of each of which are snugly received in pairs of vertical grooves 15 in the end walls 12. Each of these longitudinal strips is formed at uniformly spaced points with opposed pairs of shallow vertical grooves 19 or channels, the number of pairs being one less than the number of cross partitions 20 which will be utilized in producing the partition assembly unit. These grooves or channels 19 extend the full height of the longitudinal partition strips 18. The cross partition strips 20 intersect the longitudinal strips at right angles and are of substantially greater height than the latter (Figs. 2 and 3). With the exception of the locking center strip which is disposed medially between the ends of the unit, these cross-strips are formed with vertical notches 21 opening through their upper margins, these notches being of such width that the walls thereof fit quite snugly into the opposed grooves, or channels 19. The depth of these notches is substantially equal to the height of the longitudinal partition strips 18 so that when the strips are fully interlocked, the upper surfaces will lie in substantially the same horizontal plane and, owing to the fact that the cross partitions are of the same height as the side and end walls of the box or case, the upper margins of said side walls will be substantially flush with the upper edges of all of the partition strips.

In order that the locking center partition strip may securely retain the entire unit in the wood box, it is provided with vertical notches 22 corresponding in number to the longitudinal partition strips and opening downwardly through the lower edge. This notch formation together with registering vertical notches 23 opening through the upper edge of the longitudinal strips 18 result in such an assemblage that none of the remaining partition strips can be removed independently of the locking center strip. Opposed grooves 19^a at the lower end of the notches 23 serve to support the cross-strips 20 in proper position. A pair of fasteners 24, or clamps of any preferred form securely attach the endmost upper margins of the center locking strip to the side walls 13 of the box or case.

It will be abundantly clear, in view of the foregoing, that with properly dimensioned slots, grooves and partition strip widths, the strips may be assembled to produce a unit which can, with considerable ease, be placed in the wood box or case 10 and through the simple procedure of securing the clamps 24 in position, the box and partition assembly unit are effectively united. Re-

removal of the partition assembly unit for any reason whatsoever, involves merely bending of the clamps or fasteners 24 to separate them from the side walls 13, after which the unit 17 may be lifted out of the box and repaired as needed, or perhaps replaced in its entirety by a different cell assembly, such for example, as that shown in Fig. 4. In Fig. 4 I have illustrated a partition assembly unit 24 comprising a single longitudinal strip 25 and a single transverse strip 26, both being of the height of the box walls. This essentially is the partition assembly unit shown in Fig. 1, but omitting two longitudinal partition strips and each of the endmost pairs of cross strips so that each of the cells is of precisely the dimensions necessary to conveniently accommodate a six bottle paper-board carrier, such as those commonly used today.

Modifications may be resorted to within the spirit and scope of the appended claim.

I claim:

A rigid cell type open top bottle case comprising a generally rectangular bottom, interconnected side and end walls rising from the margin of said bottom and attached thereto, each end wall having a plurality of vertical grooves spaced uniformly along its inner face and opening through at least the upper margin of said wall, each side wall having a plurality of longitudinally spaced vertical grooves in its inner face opening through at least the upper margin of said wall, a partition assembly insertable in and readily removable from the case as a unit and comprising a plurality of longitudinal vertical 20

25

30

partition strips having their ends snugly fitted in the grooves in the end walls, each longitudinal strip provided medially between its ends with an upwardly opening notch, said notches being in alignment with each other 5 transversely of the assembly, a plurality of cross partition strips intersecting the longitudinal partition strips at right angles thereto, one only of the cross partition strips having vertically extending notches in its lower margin corresponding in number and registering with the notches in the longitudinal strips, the notches being of such depth that when the strips are assembled the upper margins of both strips are substantially flush, the remaining cross partition strips having vertical notches opening through their upper margins to accommodate 10 the longitudinal partition strips, the latter notches being of a depth approximately equal to the width of the longitudinal partition strips and fastening means releasably anchoring the ends of said one cross partitioning strip 15 only to the side walls of the case.
